(57) **CLAIM**

The ornamental design for a “golf tee,” as shown and described.

DESCRIPTION

FIG. 1 is a front top perspective view of a “golf tee” showing my new design;

FIG. 2 is a front elevational view thereof, the rear elevational view being a mirror image thereof;

FIG. 3 is a top plan view thereof;

FIG. 4 is a right side elevational view thereof;

FIG. 5 is a left side elevational view thereof; and,

FIG. 6 is a bottom plan view.
